DESIGN FOR A DRESS ENSEMBLE

Gertrude Rothchild, New York, N. Y.

Application January 3, 1941, Serial No. 97,799

Term of patent 3½ years

To all whom it may concern:

Be it known that I, Gertrude Rothchild, a citizen of the United States, residing in New York city, in the county of New York and State of New York, have invented a new, original, and ornamental Design for a Dress Ensemble, of which the following is a specification, reference being had to the accompanying drawing, forming part thereof, in which—

Figure 1 is a front view of a dress ensemble comprising a dress and jacket, showing my new design;

Figure 2 is a rear view thereof;

Figure 3 is a front view of the upper portion of the dress; and

Figure 4 is a rear view of the upper portion of the dress.

The characteristic feature of my design resides in the combination on the specific dress ensemble disclosed of the jacket member which has a wide lapel collar matching the facing around the neck and on the pockets of the dress member and with the corners thereof caught at the shoulders with a matching artificial flower, as shown.

I claim:

The ornamental design for a dress ensemble, as shown and described.

GERTRUDE ROTHCHILD.
